[57] **ABSTRACT**

An electron beam tube of the type having a fine conductive mesh adjacent a target is described, the fine mesh being clamped around its periphery between two annular members. An annular damping washer of flexible material is also clamped between the two members and extends inwards towards the picture area of the fine mesh. The two members are in addition dished away from one another and from the fine mesh in a region inwards of the clamping region so that the annular damping washer exhibits corrugations in the space between the fine mesh and the dished portion of the Clamping member which contacts the washer, the washer thereby contacting the fine mesh at a number of different places and restricting the degree to which the washer may lift away from the conductive mesh.

FIG. 2.

**CAMERA TUBE MESH CLAMPED BETWEEN
DISHED ANNULAR MEMBERS**

This invention relates to television and like camera cathode ray tubes and in particular, though not exclusively, to vidicon camera cathode ray tubes.

Many camera cathode ray tubes include a fine conductive mesh adjacent the scanned target of the tube. In a vidicon, the scanned target is a layer of photoconductive material on the inside surface of the front face of the tube envelope and the fine conductive mesh — usually referred to as the field terminating mesh — is a short distance (e.g., 3 millimetres) on the electron gun side of the target. In an image orthicon, the scan target is a secondary electron emitting layer and the mesh — usually called the target mesh — is very closely adjacent thereto on the side thereof remote from the electron gun.

A very serious defect experienced with tubes of this type is an effect which is commonly called microphony, this term having been adopted, possibly rather loosely, from analogy with microphonic effects which are produced in thermionic valves as a result of relative vibratory movements of the electrodes thereof when they are subject to mechanical shock or vibration.

Microphony in a tube of the kind described above, manifests itself in a picture reproduced from the output signals of the tube as a disturbing background of lines or striations.

In the specification of our U.K. Pat. No. 1,014,376 is described a camera tube in which, in order to reduce the effects of microphony, a damping washer, specifically an apertured mesh, is provided in contact with the main mesh referred to above. In preferred embodiments of a camera tube in accordance with Pat. No. 1,014,376, the damping mesh washer has a rectangular aperture. Camera tubes in accordance with Pat. No. 1,014,376 have been found to provide a satisfactory degree of protection against the effects of microphony.

In many cases it is an operational requirement that the tube be rotatable about its axis. This is so, for example, where the tube is to be one of a number of tubes forming part of a colour television camera. In particular, tubes of the kind using a lead oxide target, such as those known under the registered Trade Mark "Leddicon", require to be rotatable about their axis during the setting up of the camera. This requirement of being rotatable about its axis tends to preclude the use of a damping washer having a rectangular aperture. If a damping washer which is annular in form is used, however, the washer tends to distort inwardly and lift away from the main mesh towards the inner periphery of the washer, thus reducing the effectiveness of the damping provided.

The present invention seeks to provide an improved camera tube having a conductive mesh adjacent the scanned target of the tube in which the effects of this last mentioned difficulty are reduced.

According to this invention a television or like camera cathode ray tube having a fine conductive mesh adjacent the target of the tube is provided wherein said fine conductive mesh is clamped around its periphery between two annular members and an annular washer of flexible material is also clamped between said two members and in contact with said fine conductive mesh, said washer extending inwardly beyond the region of clamping by said two members towards the use-

ful picture area of the fine conductive mesh and the inner regions of said two members being dished beyond the region of clamping away from each other and said fine conductive mesh, whereby the dished portion of that clamping member in contact with said washer acts to restrict the degree to which the portion of said washer beyond the region of clamping may lift away from said fine conductive mesh so as to cause said damping washer to exhibit corrugations in the space between the fine conductive mesh and the dished portion of that clamping member.

Preferably said washer extends up to the edge of the useful picture area of the fine conductive mesh. Preferably again said washer comprises a relatively heavy copper mesh.

To quote a practical example, whereas said fine conductive mesh may have a thickness of 0.0003 inch and have 750 holes per inch, the heavy copper mesh used for the washer may have a thickness of 0.0006 inch and have 500 holes per inch.

Normally said two clamping members, the fine conductive mesh and said washer are secured together by spot welding around the outer periphery of the assembly.

The invention is further described with reference to the accompanying drawings in which,

FIG. 1 is a part sectioned broken away view of the target end of one vidicon camera cathode ray tube in accordance with the present invention, and

FIG. 2 is a part cut away perspective view of the arrangement of fine conductive mesh, damping washer and clamping members of a typical vidicon in accordance with the present invention.

Like references are used for like parts in FIGS. 1 and 2.

Referring to FIG. 1, the glass envelope of the tube is shown at 1. Within the glass envelope 1, may be seen the focusing electrode 2 of the tube. Extending beyond the focusing electrode 2 is a metal member 3 into which a support member 4 fits. Support member 4 is secured within metal member 3 by means of a plurality of tabs of which one is shown at 5. Member 3 is spaced from focusing electrode 2 by a metal spacer 6.

Support member 4 carries the fine conductive field terminating mesh 7 of the vidicon and for that reason is commonly referred to as the mesh ring. The photoconductive target of the vidicon is represented at 8.

The thin conductive mesh 7 is held in tension across the mesh ring or support member 4 by the clamping action of this last mentioned member and a further clamping member 9.

Because spacer 6, member 3 and member 4 are all of conductive material, in this example a vidicon, the thin conductive mesh 7, is operated at a potential which is the same as the operating potential of the focusing electrode 2. In other words, this example of vidicon is of the so-called "integral mesh" type.

As so far described the vidicon is as well known per se and is prone to suffer from microphony as previously described.

In accordance with the present invention, in order to reduce the effects of such microphony, a flexible damping washer 10, consisting of a heavy copper mesh of thickness 0.0006 inch and having 500 holes per inch is

also clamped between the two members 4 and 9 in contact with the fine conductive mesh 7. The members 4 and 9 with the mesh 7 and washer 10 are secured together by spot welding around the outer periphery of the assembly. The copper mesh washer 10 in this example is between the fine conductive mesh 7 and the clamping member 9. An alternative is to fit the copper mesh washer 10 between the fine conductive mesh 7 and the mesh support ring 4. In either case, the members 4 and 9 are dished away from each other beyond the region of clamping 11 provided by the two members 4 and 9, as shown. The depth of the recess formed by dishing in each case is typically 0.005 inch. The copper mesh washer 10 extends inwardly beyond the region of clamping 11 up to the edge of the useful picture area of the thin metal mesh 7, defined by the edge 12 of the clamping member 9.

As best seen from FIG. 2, the dished portion of clamping member 9 acts to restrict the degree to which the portion of mesh washer 10 beyond the region of clamping 11 would otherwise tend to distort and lift away from the fine conductive mesh 7. This causes the mesh washer 10 to exhibit corrugations in the space, formed by dishing, between the fine conductive mesh 7 and the dished portion of clamping member 9, so that in places the mesh washer 10 contacts the dished portion of clamping member 9, whilst at other places the mesh washer 10 contacts the fine conductive mesh 7.

The effect of dishing the members 4 and 9 is to permit any vibrations in the fine conductive mesh 7 to continue into the space between the dished portions of the members 4 and 9. The copper mesh washer 10, being flexible, tends to follow movements of the thin conductive mesh 7, but, being relatively dense and being relatively reluctant to move due to the distributive contact it has with the dished portion member 9, tends

to suppress such vibratory movements and thus reduce the effects of microphony.

We claim:

1. A television or like camera cathode ray tube having a fine conductive mesh adjacent the target of the tube wherein said fine conductive mesh is clamped around its periphery between two annular members and an annular washer of flexible material is also clamped between said two members and in contact with said fine conductive mesh, said washer extending inwardly beyond the region of clamping by said two members towards the useful picture area of the fine conductive mesh and the inner regions of said two members being dished beyond the region of clamping away from each other and said fine conductive mesh, whereby the dished portion of that clamping member in contact with said washer acts to restrict the degree to which the portion of said washer beyond the region of clamping may lift away from said fine conductive mesh so as to cause said damping washer to exhibit corrugations in the space between the fine conductive mesh and the dished portion of that clamping member in contact with the washer, so that said washer in said space contacts at different places said fine conductive mesh and the dished portion of that clamping member.

2. A tube as claimed in claim 1 and wherein said washer extends up to the edge of the useful picture area of the fine conductive mesh.

3. A tube as claimed in claim 1 and wherein said washer comprises a relatively heavy copper mesh.

4. A tube as claimed in claim 1 and wherein said two clamping members, the fine conductive mesh and said washer are secured together by spot welding around the outer periphery of the assembly.
